CONVEYING APPARATUS

William A. Joplin, Wollaston, Mass., assignor to
Pneumatic Scale Corporation, Limited, Quincy,
Mass., a corporation of Massachusetts

Application July 24, 1940, Serial No. 347,171

5 Claims. (Cl. 198—24)

This invention relates to conveying apparatus and more particularly to apparatus for conveying and pressing the sealed tops and bottoms of cartons after they are delivered by a packaging machine.

The invention has for an object to provide novel and improved conveying apparatus for the purpose specified which is characterized particularly by the angular disposition of the conveyer with respect to the position of the package in the packaging machine and further by the provision of transfer mechanism for transferring successive cartons after they have been sealed in the packaging machine into an inclined position in which the tops and bottoms of the cartons are substantially parallel to the top and bottom members of the conveyer.

With this general object in view and such others as may hereinafter appear, the invention consists in the conveying apparatus and in the various structures, arrangements and combinations of parts hereinafter described and particularly defined in the claims at the end of this specification.

In the drawing illustrating the preferred embodiment of the invention, Fig. 1 is a view in side elevation illustrating a sufficient portion of the conveyer and the packaging machine to enable the present invention to be understood; Fig. 2 is an enlarged detail in elevation illustrating the transfer mechanism and its relation to both the packaging machine and the conveyer of which it forms a part; and Fig. 3 is a detail in plan of a portion of the transfer mechanism and conveyer.

In the packaging of various commodities it is oftentimes desirable to deliver the completed package from the packaging machine into a conveyer disposed at an angle with relation to the horizontal, and of the type embodying upper and lower belts for exerting continued pressure upon the top and bottom of the sealed carton. Thus at times it is desirable to convey the completed packages to a succeeding floor either above or below that at which the packaging machine is located. In the usual type of packaging machine now commercially employed, the packages are held by holding members usually arranged to hold the package in a vertical position, and in order to properly present the package for reception between the upper and lower belts of an inclined conveyer of the character specified, provision is made in accordance with the present invention for automatically swinging the package from its vertical position into a position where

the ends of the package lie in planes substantially parallel to the planes of the adjacent runs of the carton engaging belts, so that as the package is introduced between the belts, minimum liability exists for jamming and otherwise distorting the package as would otherwise be the case if the package were not thus properly presented.

Referring now to the drawing which illustrates the preferred embodiment of the invention, 10 represents a packaging machine having an intermittently rotatable disk 12 provided with a plurality of carton holding members or pockets 14 mounted thereon. The cartons 16 are held 15 in a vertical position in the pockets and in the operation of the machine, the cartons are successively presented to the various instrumentalities of the packaging machine for filling, closing and adhesively sealing the cartons. When 20 the completed carton is presented to the rejecting station, indicated generally at 20, provision is made for transferring the carton from the pocket to a "dryer" or conveyer, indicated generally at 22, which comprises a pair of spaced, 25 superposed elongated belts 24, 26 arranged to apply continuous pressure upon the ends of the carton to firmly set the adhesively sealed flaps of the carton while the adhesive is drying and during the conveyance thereof to the point of delivery.

In the illustrated embodiment of the invention, the dryer 22 is inclined upwardly at an angle with respect to the horizontal level of the packaging machine in order that the cartons may be delivered to a different level, such as up to a packing room located on the floor above. As herein shown, the receiving end of the dryer may be supported from the packaging machine by a bracket 30 and the delivery end may be supported from above by a ceiling bracket 32 and a bracket 34 attached to the dryer frame. The upper belt 24 is arranged to run over a driving pulley 36 and idler pulley 38 disposed at either end of the conveyer and supported in the upper framework 40 of the dryer. Guide rolls 42, 44, 46 may also be provided for the upper belt 24, and an intermediate idler roll 48 is adapted to be adjusted to provide the proper tension in the belt. Pressure is directed against the top of the lower run of the belt 24 by a series of weighted rollers 50 which may be journaled in the upper frame 40. The lower belt 26 may be similarly mounted to run over a driving pulley 52 and an idler 54 supported in the lower framework 56, the upper run of the belt being supported along

its underside by a plurality of rollers 58. The belts 24, 26 have their entrance ends disposed adjacent to but spaced from the carton holding member 14 and are arranged to be driven from a motor 60 mounted on the bracket 34. Connections from the motor 60 to the driving pulleys 36, 52 include sprocket and chain connections 62, 64 as clearly illustrated in Fig. 1.

In accordance with the present invention, provision is made for transferring the carton from its vertical position in the carton supporting pocket 14 into a position between the entrance ends of the angularly disposed parallel pressure belts 24 and 26 of the dryer or conveyor in a manner such as to present the ends of the carton substantially parallel to said belts. As herein shown, the transferring member comprises hook shaped arms 70, 72 arranged to be moved into the path of the carton as it is intermittently moved into operative position with relation to the rejecting station, and which engage the carton above and below the carton holding member 14 as illustrated in Figs. 2 and 3. The transfer members 70, 72 are mounted upon a carriage 74 provided with rollers 76 and which is arranged to be moved along a curved guide bar 78 through connections from an operating cam 80. The operating cam 80 is mounted fast on a cam shaft 82 forming part of the packaging machine and the connections from the cam to the movable carriage include a link 84 connected to one arm 86 of a bell-crank pivotally mounted on a stud 88 fast in a bracket 90 attached to the lower frame 56 of the dryer. The second arm 92 of the bell-crank is connected by a link 94 to one arm 96 of a cam lever, the second arm 98 being provided with a cam roll 100 cooperating with the closed cam 80. As herein shown, the curved or arcuate guide bar 78 is supported by side bars 102, 104 attached to the dryer frame, and in operation, the carriage 74 is moved from the position shown in full lines in Fig. 2 to the dotted line position shown therein to swing the carton from its vertical position to an inclined position presenting the ends of the carton substantially parallel to the pressure belts 24, 26. Suitable upper and lower guide rails 106, 108 secured to the dryer frame and disposed in a plane substantially level with the lower run of belt 24 and the upper run of belt 26, respectively, may be provided in order to support the ends of the carton during the transferring operation.

From the above description of the preferred embodiment of the invention, it will be understood that the invention may take different forms and may be used with advantage in those instances where it is desired to convey the completed carton from the packaging machine to a different level and that the transferring device is adapted to change the position of the carton from its vertical position in the packaging machine to an angular position to present the ends of the carton substantially parallel to the conveying apparatus.

While the preferred embodiment of the invention has been herein illustrated and described, it will be understood that the invention may be embodied in other forms within the scope of the following claims.

Having thus described the invention, what is claimed is:

1. The combination with a rotary packaging machine provided with a carton holding member having provision for operatively supporting a carton in a vertical position, of an elongated conveyor comprising a pair of spaced, superposed

carton engaging belts having their adjacent runs parallel, said conveyor being angularly disposed with respect to said vertical carton to convey said carton to a different elevation, the entrance ends of said belts being disposed adjacent to but spaced from said carton holding member; and means operatively arranged relative to said belts and carton holding member for transferring said carton from said carton holding member to a position between said belts with said carton inclined so that the ends of said carton are disposed substantially parallel with said adjacent runs of said belts, said transfer means including carton engaging means and means for moving said carton engaging means in a curved path between said carton holding member and said belts.

2. The combination with a rotary packaging machine having a plurality of pockets mounted to rotate therewith and adapted to operatively support packages in a vertical position, of an angularly disposed conveyor for conveying said packages to a position at a different elevation, said conveyor including two spaced, superposed conveyor belts having their adjacent runs parallel and between which said packages are adapted to be received, the entrance ends of said belts being disposed adjacent to but spaced from a given pocket; transfer means carried by said conveyor for swinging a package through said space between said given pocket and said ends of said belts and simultaneously tilting said package from its vertical position into an inclined position for reception between said belts so that the ends of said package are disposed substantially parallel with said adjacent runs of said belts, said transfer means including hook-shaped arm means arranged to engage a package while it is vertically supported in said given pocket, means for moving said arm means in an arc, and means lying in a plane substantially level with the upper run of the lower conveyor belt for supporting said package at the bottom thereof during transfer.

3. The combination with a rotary packaging machine provided with a carton holding member having provision for operatively supporting a carton in a vertical position, of an elongated conveyor comprising a pair of spaced, superposed carton engaging belts having their adjacent runs parallel, the entrance ends of said belts being disposed adjacent to but spaced from said carton holding member, said conveyor being angularly disposed with respect to said carton as the latter is held by said carton holding member and being adapted to convey said carton to a different elevation; and means operatively arranged relative to said belts and said carton holding member for transferring said carton from said carton holding member to a position between said belts with said carton inclined so that the ends of said carton are disposed substantially parallel with said adjacent runs of said belts, said transfer means including a pair of carton engaging arms adapted to engage a carton while it is supported in said carton holding member, a movable carriage, said arms being mounted upon said carriage, means including a cam for moving said carriage and said arms in a curved path, and means engageable by the bottom of said carton for supporting said carton during such movement.

4. The combination with a rotary packaging machine having a plurality of pockets mounted to rotate therewith and adapted to operatively support packages in a vertical position, of an

angularly disposed conveyer for conveying said packages to a position at a different elevation, said conveyer including two spaced, superposed conveyer belts having their adjacent runs parallel and between which said package is adapted to be received, the entrance end of said conveyer being spaced from said pocket; and transfer means operatively arranged relative to said conveyer and said carton holding member for swinging a package from its vertical position through the space between said entrance end of said conveyer and said pocket and into an inclined position for reception between said belts with the ends of said package disposed substantially parallel with said adjacent runs of said belts, said transfer means including a pair of hook-shaped arms arranged to engage a side of said package adjacent the upper and lower ends thereof while said package is supported in said pocket, means for guiding said arms for movement in a curved path, means for moving said arms in said curved path, and means engageable by the bottom of said package for supporting said package during transfer.

5. The combination with a rotary packaging machine provided with a carton holding member having provision for operatively supporting a

carton in vertical position, of an elongated conveyer comprising a pair of spaced, superposed carton engaging belts having their adjacent runs parallel, said conveyer being angularly disposed with respect to said carton as the latter is held by said carton holding member and being arranged to convey said carton to a different elevation, the entrance end of said conveyer being disposed adjacent to but spaced from said carton holding member; and means carried by said conveyer for transferring said carton from said carton holding member to an inclined position between said belts with the ends of said carton disposed substantially parallel with said adjacent runs of said belts, said transfer means including a pair of carton engaging arms arranged to engage said carton while it is supported in said carton holding member, a movable carriage, said arms being mounted upon said carriage, a curved, stationary guide bar, said carriage being mounted for reciprocating movement upon said curved guide bar, means including a cam for reciprocating said carriage along said curved guide bar; and means for supportingly engaging the bottom of said carton during transfer.
